CLAIM

The ornamental design for a fire pit support as shown and described.

DESCRIPTION

FIG. 1 is a perspective view of a first embodiment of the fire pit support showing my new design.

FIG. 2 is a front elevation view thereof.

FIG. 3 is a right-side elevation view thereof, the left-side and rear elevation views being identical.

FIG. 4 is a top plan view thereof.

FIG. 5 is a perspective view of a second embodiment of the fire pit support showing my new design.

FIG. 6 is a front elevation view thereof.

FIG. 7 is a right-side elevation view thereof, the left-side and rear elevation views being identical; and,

FIG. 8 is a top plan view thereof.

The dashed lines shown in the drawings are for purposes of illustrating portions of the article that form no part of the claimed design.
